CALL INDICATOR

Herbert R. Warnke, East Orange, N. J., assignor
to United States Instrument Corporation, East
Orange, N. J., a corporation of New Jersey

Application July 5, 1939, Serial No. 282,869

11 Claims. (Cl. 179—5.5)

This invention relates to call indicators or annunciators of the visual type, for general use in suitable applications and, in particular, useful in connection with telephone systems of the direct connected type, i. e., in which no central switchboard is employed, the several stations being directly connected to one another, or to a "master" station. The invention has for its general object the provision of means for visibly indicating the receipt of incoming calls, whereby if a call is received at a given station while the instrument at that station is in use, the call will nevertheless be registered by means of a visible signal which indicates the source of the call, so that the called party may return the call after completing the current conversation.

An important feature of the present invention is that the indicator will register all calls received, so that if a party is absent from his station, and 20 out of hearing of the usual audible signal, he will nevertheless be apprised, upon his return, not only of the fact that he has been called, but of the identity of the calling station or stations.

Another object of the present invention is the provision of a visual indicator of the kind described, of novel and compact construction, incorporated in the base of a telephone instrument, whereby the necessity of employing an annunciator of the cumbersome and expensive wall or desk type is obviated. A further object is the provision of such an indicator in association with the usual station selector switch, in such a manner that the indicator signal is cancelled when the selector switch is moved to establish a talking circuit between the called station and the calling station.

Another object is the provision of a visual indicator of the kind described, said indicator being normally in series with the usual audible signal, together with means whereby a shunt circuit is established through the visual indicator when the instrument is in use, so that incoming calls will be registered although the audible signal will remain silent.

Other and further objects, features and advantages of the present invention will be apparent to one skilled in the art from the following description taken in connection with the accompanying drawings in which:

Figure 1 is a front elevation of a telephone instrument embodying the present invention;

Figure 2 is a front elevation of the selector switch and call indicator mechanism;

Figure 3 is a side elevation of the mechanism of Figure 2;

Figure 4 is a rear elevation of the mechanism of Figure 2;

Figure 5 is a vertical section on line 5—5 of Figure 2;

Figure 6 is a fragmentary section on line 6—6 of Figure 5;

Figure 7 is an enlarged vertical section corresponding to the upper portion of Figure 5; and

Figure 8 is a circuit diagram illustrating one mode of employing the present invention in a telephone system.

In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

In the present instance, the invention will be described as embodied in a direct connected telephone system of the so-called "master station" type, in which one station, designated the "master" station, is connected with each of a plurality of subsidiary stations, the subsidiary stations not being connected to one another. In such a system, each subsidiary station may only call the master station, but the latter may call each of the subsidiary stations. In such a system, the call indicator of the present invention need only be incorporated in the instrument at the master station. However, it will be understood that the call indicator of the present invention is capable of many and varied applications, and is not limited to use in connection with a "master station" system.

Referring to the drawings, Figure 1 illustrates a telephone instrument at the master station, comprising a base portion 10 and a hand set 11. The details of the instruments (receiver and transmitter) within the hand set form no part of the present invention, and will not be described herein. The base portion 10 is provided with a dial plate 12 numbered (in the illustrated embodiment) from 1 to 6, for cooperation with the pointer 13 of a station selector switch to be hereinafter described. Adjacent each numbered point on the dial plate 12, the casing wall of the instrument base is apertured to provide windows 14. Centrally of the dial plate 12, as best seen in Figure 3, the casing wall is tapped to receive a threaded bushing 15 in which is rotatably mounted the shaft 16 of the selector switch. The shaft 16 extends rearwardly through an aperture 17 in

a base plate 18, which latter is provided with a rearwardly extending annular flange 19 defining a well 20. A cam 21 is disposed within the well 20 and is secured upon the rearward end of the shaft 16 by means of a screw 22.

The selector switch comprises a front plate 23 and a disc 24 of insulating material, spaced from the base plate 18 and from each other by bolts 25 and sleeves 26. The insulating disc 24 carries a series of contact points adapted to be selectively engaged by a rotating contact member, the contact points and rotating contact member being connected in the circuit as illustrated diagrammatically in Figure 8. The details of the selector switch form no part of the present invention, and need not be further described herein, but by way of explanation it may be noted that a suitable type of selector switch is described and illustrated in United States Patent No. 2,012,492.

A series of indicator arms 27, one for each window 14, are pivoted about the periphery of the base plate 18. Each arm 27 comprises a rearward portion 28 normally disposed parallel to the shaft 16 of the selector, an inwardly and forwardly extending portion 29, and a radially extending flag portion 30 adapted to move behind one of the windows 14. The outer end of the forward surface of each flag portion 30, being normally disposed behind a window 14, is preferably colored like the casing of the instrument base 10, while the inner end of the same surface is coated with material of a contrasting color, so that it may be readily discerned when an arm 27 has moved so as to bring the inner end of the flag 30 opposite a window 14.

The indicator arms 27 are constantly urged so as to cause the flag portions 30 to move outwardly, by means of small springs 31 (Figures 6 and 7), but are normally maintained in the position illustrated by means of latch members 32. Each latch member 32 is loosely mounted on a rod 33 which extends between the base plate 18 and a backing plate 34, which latter is secured to the rearward edge of the flange 19 by means of screws 35. Each latch 32 is enabled to pivot rearwardly, being guided to prevent rotation by a pin 36 mounted in the base plate 18 and extending through a suitable aperture in the latch member. The latch members are normally urged forwardly against the rear face of the base plate by means of springs 37 surrounding the rods 33. A plate 38 of insulating material is disposed rearwardly of the backing plate 34, being secured in place by the screws 35.

A small electromagnet 39 is secured to the forward surface of the backing plate 34 adjacent each latch member 32, the magnets 39 being connected in the circuit as diagrammatically illustrated in Figure 8. The latch members 32 are formed of magnetic material, for example iron, and it will be readily apparent that when a magnet 39 is energized, the corresponding latch member 32 will be attracted, disengaging it from the corresponding arm 27 and permitting the latter to pivot in response to the tension of its associated spring 31. By this movement, the flag portion of the arm 27 is moved outwardly with respect to the shaft 16, bringing the inner, contrastingly colored portion of the flag member opposite the corresponding window 14 and indicating that a call has been received from the corresponding subsidiary station.

Adjacent each indicator arm 27 there is provided a push rod 40 (Figure 6), which extends

through a radial aperture in the base plate 18 and into the well 20 adjacent the cam 21. The latter is provided with two adjacent peripheral protuberances 41, so arranged that the valley between them occupies the same circumferential relationship to the shaft 16 as do the pointer 13 and the rotary switch arm of the selector switch. When the latter is turned to the dial position corresponding to the calling station, so as to complete a talking circuit between the calling station and the called station, one or another of the protuberances 41, depending upon the direction of movement, will engage the inner end of the push rod 40 and force the latter outwardly into engagement with the portion 28 of the corresponding indicator arm 27, moving the latter outwardly against the tension of the spring 31. When this occurs, the latch member 32 is permitted to pivot forwardly under the pressure of the spring 37, and again engages beneath the edge of the rearward end of the arm 27, it being understood that the magnet 39 is now de-energized. If the call is received when the pointer 13 happens to be in a position corresponding to the calling station, the corresponding indicator arm will move as above described, the push rod 40 engaging the cam 21 in the valley between the two protuberances 41, as illustrated in Figure 6. In this case, the indicator may be reset at the conclusion of the call by moving the pointer 13 and cam 21 in either direction.

The call indicator of the present invention is applied in a "master station" system in the following manner: In Figure 8 there is illustrated a system adapted for a master station, shown in the center of the figure, and six subsidiary stations, only two of the latter being shown, however. The junction box 50, illustrated diagrammatically, furnishes a convenient mode of connecting the various subsidiary station circuits to the master station. The magnets 39 of the call indicator are shown adjacent the selector switch dial 12, and a buzzer or other audible signal is represented at 51. The latter is shunted by a 5 or 10 ohm resistance 51', in order to pass sufficient current to operate the visual call indicator. It will be understood that the magnets, selector switch, and audible signal are all preferably arranged within an instrument base, such as the base 10 of Figure 1, which also carries plungers 52 and 53, which are urged upwardly by spring contact arms 54 and 55, respectively, but are normally held in a depressed position by the hand set 11, which rests upon the instrument base when not in use.

The telephone instruments in the hand sets 11 may be of the voice-powered type, requiring no external energy source, or of any suitable type. In the present case it is assumed that the voice-powered instruments are used, and no source of electrical energy is shown except the battery 56 which furnishes energy for operating the visible and audible call signals.

In addition to the contact arms 54 and 55, each instrument base carries spring contact arms 57 and 58, adapted to cooperate with the arms 54 and 55, respectively, and contact arms 59 and 60, adapted to cooperate with each other. A strip of insulation 61 separates contact arms 55 and 60. In addition, the master station base carries a contact arm 62 which is engaged by the arm 54 when the hand set is raised. In Figure 8, the several plungers 52 and 53 are shown in normal position, i. e., the position which they occupy when the instrument is not in use. It will be noted that stations Nos. 1 and 2 are each connected by four

wires to the master station, but are not connected to each other.

Assuming, now, that station No. 1, on the left, desires to call the master station, the hand set is lifted, allowing plungers 52 and 53 to rise. Plunger 52, which may be called the ringing button, is then depressed closing a circuit through contact arm 54, conductor 63, junction box 50, conductor 64, battery 56, conductors 65 and 66, 10 in parallel through the buzzer 51 and resistance 51, through conductor 67, contact arms 60 and 59, conductors 68, 69, the left hand magnet 39, conductor 70, junction box 50, and conductor 71 back to contact arm 57. Thus the buzzer 51 and 15 visual indicator will both be actuated. If now the party at the master station lifts the hand set and turns the selector switch to station No. 1 on the dial, the visual indicator is reset as previously described, and a talking circuit is established 20 from the hand set 11 of station No. 1 through conductors 72, 73, junction box 50, conductor 74, the switch arm of the selector switch (corresponding to pointer 13) conductor 75, through the hand set 11 of the master station, conductor 76, contact arms 58, 55, conductor 77, junction box 50, conductor 78, contact arms 55 and 58 of station No. 1, and conductor 79 back to hand set 11 of station No. 1.

If the master station is talking to another subsidiary station when station No. 1 calls, the circuit through buzzer 51 will be open, by reason of contact arms 59 and 60 being separated, but a circuit will be completed through the visual call indicator by means of conductor 80, contact arms 54 and 62, which are now in engagement, and conductor 81. Thus the buzzer will not sound, but the visual indicator will be actuated.

When the master station desires to call a subsidiary station, the pointer 13 is positioned accordingly, the hand set lifted, and the plunger 52 at the master station is depressed. It is believed unnecessary to trace the resulting circuit, except to point out that the circuit includes the contact arms 59 and 60 at the subsidiary station. 45 When the hand set at the latter station is lifted, the contact arms 59 and 60 separate and contact arms 55 and 58 engage, closing the talking circuit.

One important advantage of the present invention, in connection with master station systems, is that it is unnecessary to employ code ringing to apprise the master station of the identity of the calling station, which is ordinarily the case in order that the selector switch 55 may be correctly operated to close the talking circuit.

While the present invention is primarily intended for telephone use, it obviously will be useful in other applications, as in elevator call 60 systems and many other types of electrical signaling systems.

Having thus described the invention, what is claimed as new and desired to be secured by Letters Patent is:

65 1. In a telephone system of the direct connected type, a plurality of telephone instruments at different stations, electrical conductors connecting said instruments, a station selector switch at one of said stations for selectively connecting the instrument at said station with said other instruments, and a call indicator associated with said selector switch, said call indicator comprising a plurality of movable members corresponding to the other stations in said system, electromagnetic 70 means associated with each said movable mem-

ber for actuating the same to give a visible signal, each said electromagnetic means being in circuit with one of said other stations, and means associated with said selector switch for resetting said movable members to normal position when the corresponding stations are selected.

2. In a system according to claim 1, an audible signal device at said station and normally in series with said electromagnetic means, and means for shunting said audible signal device when the instrument at said station is in use.

3. In a telephone system of the direct connected type, a plurality of telephone instruments at different stations, electrical conductors connecting said instruments, a station selector switch at one of said stations for selectively connecting the instrument at said station with said other instruments, and a call indicator associated with said selector switch, said call indicator comprising a plurality of movable members corresponding to the other stations in said system, latch means associated with each movable member for maintaining it in normal position, means urging each said member to indicating position, electromagnetic means associated with each said member and adapted when energized to actuate said latch means to release said member, each said electromagnetic means being in circuit with one of said other stations, and means associated with said selector switch for resetting said members and latch means when the corresponding stations are selected.

4. In a telephone system of the direct connected type, a plurality of telephone instruments at different stations, electrical conductors connecting said instruments, a station selector switch at one of said stations for selectively connecting the instrument at said station with said other instruments, and a call indicator associated with said selector switch, said call indicator comprising a plurality of movable members corresponding to the other stations in said system, electromagnetic means associated with each said movable member for actuating the same to give a visible signal, each said electromagnetic means being in circuit with one of said other stations, and means associated with said selector switch for resetting said movable members to normal position when the corresponding stations are selected, said last means comprising a cam rotatable with said selector switch and means associated with each said movable member and adapted to project into the path of said cam when said member is in indicating position.

5. In a telephone system having a plurality of stations, a telephone instrument at one of said stations comprising a casing, a selector switch mounted in a wall of said casing, a plurality of numbered windows in said casing wall and surrounding said selector switch, said windows corresponding to the other stations in said system, a movable member arranged inside said casing adjacent each said window, means associated with each said movable member for causing it to give a signal which is visible in its associated window whenever a call is received from the corresponding station, and means associated with said selector switch for resetting said movable members.

6. In a telephone system having a plurality of stations, a telephone instrument at one of said stations comprising a casing, a selector switch mounted in a wall of said casing, movable members arranged adjacent said selector switch and corresponding respectively to the other stations 75

in said system, means for moving each said member to indicating position when a call is received from the corresponding station, and means for resetting said members to normal position.

- 5 7. In a telephone system having a plurality of stations, a telephone instrument at one of said stations comprising a casing, a selector switch mounted in a wall of said casing, movable members arranged adjacent said selector switch and corresponding respectively to the other stations in said system, means for moving each said member to indicating position when a call is received from the corresponding station, and means for resetting said members to normal position.
- 10 15. Said last means comprising a cam rotatable with said selector switch and means associated with each said movable member and adapted to project into the path of said cam when said member is in indicating position.
- 20 25. 8. In a telephone system having a plurality of stations, a telephone instrument at one of said stations comprising a casing, a selector switch mounted in a wall of said casing, a plurality of numbered windows in said casing wall and surrounding said selector switch, said windows corresponding to the other stations in said system, a movable member arranged inside said casing adjacent each said window, means associated with each said movable member for causing it to give a signal which is visible in its associated window whenever a call is received from the corresponding station, and means associated with said selector switch for resetting said movable members, said last means comprising a cam rotatable with said selector switch and means associated with each said movable member and adapted to project into the path of said cam when said member is in indicating position.
- 30 35.

9. In a telephone system comprising a master station and a plurality of other stations directly connected to said master station, a station selector switch at said master station for selectively connecting the instrument at said station with said other instruments, and a call indicator associated with said selector switch, said call indicator comprising a plurality of movable members corresponding to the other stations in said system, electromagnetic means associated with each said movable member for actuating the same to give a visible signal, each said electromagnetic means being in circuit with one of said other stations, and means associated with said selector switch for resetting said movable members to normal position when the corresponding stations are selected.

10. A call indicator comprising a plurality of movable members each having a flag portion, latch means associated with each movable member for maintaining it in normal position, means urging each said member to indicating position, electromagnetic means associated with each said member and adapted when energized to actuate said latch means to release said member, means for selectively energizing said electromagnetic means, and means for resetting said movable members.

11. A call indicator according to claim 10, said last means comprising a movable cam for resetting said movable members and a pointer movable with said cam and cooperatively associated with said movable members to indicate the position of the cam relative thereto.

HERBERT R. WARNKE.
